Attorney.

UNITED STATES PATENT OFFICE

JAY LAVENSON, OF JENKINTOWN, PENNSYLVANIA, ASSIGNOR TO PIONEER SUSPENDER COMPANY, A CORPORATION OF PENNSYLVANIA

BUCKLE

Application filed June 30, 1931. Serial No. 547,868.

My invention relates to improvements in buckles, especially belt buckles for personal wear. The object is to provide improved concealed anti-friction means for engaging the belt or strap when the same is pulled in position of adjustment through the buckle so that the belt or strap will not engage or rub against any stationary part of the buckle during said adjustment, especially during the tightening movement of the strap.

It is of course known in the art to provide buckles with cross-bars either as rollers or else to mount upon the cross-bar loose sleeves which shall act as antifriction rollers. These are especially common in buckles used on harness, but such devices are visible, and thus prevent the desired finish of the front face or surface of the buckle.

Referring to the drawings, which illustrate, merely by way of example, a suitable embodiment of the invention:

Fig. 1 is a view in perspective of a buckle embodying the invention.

Fig. 2 is a section on line 2, 2 of Fig. 1, except that the buckle tongue is elevated and the belt or strap is shown in the position during adjustment or tightening. The section is on an enlarged scale.

Similar numerals refer to similar parts throughout the several views.

The buckle illustrated is of standard type, having the rear cross-bar 5, the front cross-bar 6 and the connecting side bars 7. At the middle of the rear cross-bar 5 is pivotally mounted the tongue 8, the free end of which is adapted to overlie the front cross-bar 6. In such type of buckle the front cross-bar 6 is relatively wide and forms the attractive or decorative part of the buckle when in use.

In accordance with the present invention, the under and inner edge of the front cross-bar 6 is recessed or channeled, as at 9, to receive the roller 10 pivoted at its ends, as at 11, in the bearings 12 formed in the side frame 7.

The recess or groove 9, and the diameter of the roller 10 are of such relative dimensions that the periphery of the roller will extend slightly beyond the vertical plane of the inner edge or surface of cross-bar 6 and also

beyond the horizontal plane of the under surface of said cross-bar.

It will thus be seen that when the strap or belt 13 is inserted through the buckle and pulled in the direction of the arrow, Fig. 2, it will only engage the roller 10 and will be entirely out of contact with the adjacent surfaces of the cross-bar 6.

It will be especially noted that the belt, which will normally be pressed against the front cross-bar of the buckle when surrounding the waist of the wearer, is effectually held out of contact with the front cross-bar because the periphery of the roller extends substantially beyond the plane of the underside or surface of the said cross-bar, thus preventing fraying or wear on the surface of the belt and also facilitating the operation of adjustment.

While it is usually desirable to have the periphery of the roller extend beyond the planes of both inner and under surfaces of the cross-bar, it is of especial importance that said periphery extend substantially below the plane of the under side of said bar, since the pressure of the wearer's body upon the belt, will normally cause the greater pressure of the belt against the underside of the buckle during the tightening operation.

By the term "under side" is meant the side that is toward the body of the wearer.

What I claim is:

1. A belt buckle having a portion extending transverse the longitudinal extension of the belt, and antifriction means associated therewith and adjacent thereto and positioned entirely below the upper surface of said transverse portion, and having a part only of its periphery projecting beyond the planes of the inner edge and of the under side of said transverse portions.

2. A belt buckle, having a front cross-bar provided with a channel adjacent its inner and under sides, and a roller operating in said channel having a portion of its periphery extending beyond the plane of said underside.

3. A belt buckle, having parallel side members, a front cross-bar provided with a chan-

nel adjacent its inner and under sides, and a roller having pivot bearings in the side members and operating in said channel and having a portion only of its periphery extending beyond the plane of said inner side.

4. A belt buckle, having a front cross-bar provided with a channel adjacent its inner and under sides, and a roller operating in said channel having a portion of its periphery extending beyond the planes of said inner and under sides.

5. A belt buckle comprising a frame having side portions extending parallel with the longitudinal extension of the belt and transversely extending end portions, a tongue pivotally mounted on one end portion, the other end portion provided with anti-friction means positioned entirely below the upper surface of said end portion and having a belt engaging part of its periphery projecting below the plane of the underside of said end portion.

JAY LAVENSON.
